UNITED STATES PATENT OFFICE.

FRANS HENRIK AUBERT WIELGOLASKI, OF CHRISTIANIA, NORWAY.

METHOD AND APPARATUS FOR STRETCHING OUT LONG DOUBLE OR MULTIPLE ELECTRIC ARCS.

1,320,431.

Specification of Letters Patent. Patented Nov. 4, 1919.

Application filed September 28, 1916. Serial No. 122,625.

To all whom it may concern:

Be it known that I, FRANS HENRIK AUBERT WIELGOLASKI, of Odins gate 1, Christiania, in the Kingdom of Norway, having invented certain new and useful Improvements in Methods and Apparatus for Stretching Out Long Double or Multiple Electric Arcs, do hereby declare that the following is a full, clear, and exact description of the same.

It is already known that long single electric arcs may be stretched out or extended in this manner, that the first part of the stretching-out takes place along so-called horn-shaped electrodes, whereas the continued stretching-out takes place by each end of the arc being driven into its separate furnace space by means of a gas current (see applicant's Patent No. (U. S.) 1,061,892 (Canada) 151774).

The present invention comprises a somewhat similar method of stretching out double or multiple electric arcs, but this method is characterized by this that the arc—after having first been somewhat stretched out along horn-shaped electrodes—is hung with its ends upon the outer ends of these horn-shaped electrodes and is thereafter divided, the stretching-out being then continued in each portion of the arc, the ends of such portions by the said portions each being blown into its furnace space by means of a blast of gas or air.

The invention is illustrated in the accompanying drawing, in which:

Figures 1 and 2 show in longitudinal elevation and in section respectively an example of a suitable arrangement for carrying out the method by a single-phase alternating current and by direct current.

Figs. 3 and 4 show in longitudinal elevation and in section respectively an example of a similar arrangement operating by three-phase alternating current.

Figs. 5, 6, 7 and 8 show in sections how electrically conducting walls of the furnace space may be built up and how the furnace spaces may if desired (as shown in Figs. 7 and 8) be connected together through lots for equalizing the gas pressure throughout the system.

Fig. 9 shows an arrangement of apparatus for using horn-shaped electrodes with

ring-shaped electrodes at the tops thereof, or optionally rotating electrodes. 55

Figs. 10 and 11 show different kinds of tubes that may be employed, these being shown in cross-section.

Referring to Figs. 1 and 2 the reference numerals 1—2 and 3—4 represent horn-shaped electrodes, between which the arc is started and extended in the manner which is characteristic and known for such electrodes, until the arc burns between the ends —2— and —4— of the horn-shaped electrodes. In this position the arc, on account of its always upwardly curved shape, will strike against the adjacent edges —5— and —7— of the electrically conducting and mutually electrically connected furnace pipes 60 5—6 and 7—8, whereby the arc, as indicated diagrammatically in the drawing, is divided into two separate series-connected arcs, the new-formed ends of which are each, by 65 means of its separate gas current, driven up 70 5—6 and 7—8 respectively as indicated by the arrows. An electrical connection between the two furnace parts is designated by the rod or wire 9 or 9^a respectively. This connection 75 obviously may be arranged in any other suitable manner. Thus the furnace pipes may be made in an integral piece as shown in Figs. 5 and 7. The furnace spaces may be electrically conducting throughout or be provided with separate electric conductors. 80 85

In the same manner the stretching-out takes place in a three-phase arrangement, which is shown in Figs. 3, 4, 6 and 8. A detailed explanation of these figures is unnecessary. However, it should be mentioned, that it may be advantageous, especially in arrangements operated by poly-phase current, to arrange an auxiliary electrode (a climb electrode) —10—, Fig. 4, which is 90 95 without any electric connection with the current source and projects up between or is located directly above the starting point of the arc between the horn-shaped electrodes. Hereby a star-coupling of the arcs is secured, until they are divided. By making this auxiliary electrode for instance tapered and movable in longitudinal direction by means of magnetic influence produced either by the whole working current, by a shunt 100 105 of the same or by an induction-current pro-

duced thereby or by similar means, a re-starting of the arc may be secured to an increased degree, when the arc has been interrupted for some reason.

5 The horn-shaped electrodes may of course be arranged in any suitable manner and be provided with other auxiliary means for starting than those mentioned above.

10 As shown in Fig. 9, the horn-shaped electrodes may also be completely or partly replaced by rotating electrodes (see applicant's (U. S. A.) patent application No. 78427). The ends of the horn-shaped electrodes may also be made ring-shaped, so 15 that the arc end may be allowed to rotate upon this ring-shape. The forms of apparatuses here mentioned may further be provided with suitable resistance devices.

20 In Fig. 9, 12 is an annular end of the horn-shaped electrode. 13 is a rotating electrode, which partly can be substituted for the other horn-shaped electrode. If the last mentioned horn-shaped electrode is entirely replaced (substituted) by a rotating electrode, 25 the diameter of this must be greater as shown in dotted lines at 11.

110 shows in dotted lines how also the first mentioned horn-shaped electrode partly may be substituted by a rotating electrode.

30 The one furnace pipe 5—6 is here shown undivided, whereas the other furnace pipe 7—8 is divided into sections 16, 17 and 18 which are mutually connected through the resistance 19. 14 and 15 are similar resistances which connect the individual parts 20 and 21 of the horn-shaped electrode at the base of the pipe 7—8 with each other. 25 12—13 indicate the source of electricity. 12—13 indicate the source of electricity. 9 is the electrical conducting connection between the two furnace pipes.

40 Fig. 10 shows a section of an all metal

pipe which can be used in any of the above constructions. Fig. 11 shows a pipe made principally of non-conducting material 27 having electrically conductive insets or slabs 28 set into its interior, to serve as conductors.

Having now described my invention, what I claim as new and desire to secure by Letters Patent is:

1. A method of stretching out long double 5 or multiple electric arcs, which comprises producing an arc between electrodes, blowing portions of said arc into each of a plurality of separate tubular furnaces, the walls of which are in electrical connection with 5 each other.

2. An electric furnace arrangement comprising a plurality of furnace pipes in combination with one set of electrodes arranged at one end of said pipes, said pipes being 6 constructed, at least in part, of electrically conductive material, and said pipes being in electrical connection with each other.

3. An electric furnace arrangement comprising not less than three furnace pipes in 6 combination with one set of horn-shaped electrodes arranged at one end of said set of pipes, said pipes being constructed, at least in part, of electrically conductive material, and said pipes being in electrical connection 7 with one another.

4. In the arrangements of apparatus specified in claims 2 and 3, the construction of the pipes partially, but not entirely of electrically conductive material.

In testimony whereof I have signed my name to this specification in the presence of two subscribing witnesses.

FRANS HENRIK AUBERT WIELGOLASKI.
